FIG. 1.

FIG. 2.

INVENTOR.
PERCY VARNEY.

By *James P. Riffle*

ATTORNEY.

UNITED STATES PATENT OFFICE

PERCY VARNEY, OF REDWOOD CITY, CALIFORNIA

SIPHON STARTER

Application filed March 14, 1929. Serial No. 346,882.

The present invention relates broadly to improvements in siphons, but more particularly to siphon starters adapted to start siphon action in those being employed for the transference of liquids and beverages from one container to another.

The primary object of the invention is the provision of a simplified form of starter for use in connection with siphons for the purpose of starting siphon action, or the flow of liquids therethrough, rather than to rely upon suction applied through the mouth to the long arm of the siphon for the creation therein of a lowered pressure as a starting means, as is common practice.

A further object of the invention is to provide a siphon starter of the class designated that is not alone positive in action, but is also durable, and one that may be cheaply constructed from any suitable material.

Other objects and advantages of the invention will appear as this specification progresses, and be fully set forth in the claim hereto appended.

In the accompanying drawings, forming a part of this specification, and in which similar characters of reference, throughout, refer to like parts:

Figure 1 is a plan view illustrative of my improved siphon starter in position for use, with one end, or its short arm, immersed in the liquid of a container; and

Figure 2 is a vertical sectional view of the same, showing, in addition to that shown in Figure 1, the starter proper, the compressible bulb, and the discharge or long arm connected therewith and the clamping means borne thereby.

Referring with greater particularity to the drawings, in which the preferred form of my invention is disclosed, the numeral 5 indicates, in a general way, the starter, and 6 a container of liquid to be siphoned.

The siphon starter proper 5 embodies a vessel of invert cylindro-conical character constructed of any suitable non-corrodible material, preferably, thin sheet metal, the lower conically-shaped portion 8 terminating in a nipple 9, and the cylindrically-shaped

upper portion 10 provided with a tap 11 terminating in a nipple 12.

A compressible bulb 13 having a neck 14 is fitted over the nipple 12, and a flexible connection 15 secured to the nipple, this connection being provided with a suitable clamp 16 for cutting off the flow of liquid from the chamber 17.

A nipple 18 is provided for the cylindrical section 10 and a connection 19 fitted thereover with its outer extremity extending into the fluid content 21 of the container 6.

The operation of the starter is substantially as follows:

Assuming that it is desired to transfer the liquid content 21 of the container 6 to bottles, or other receptacles, the clip 16 is closed, as shown in Figure 2. The bulb 13 is then compressed, forcing the air in vessel 17 out through the end 20 of the tube, thereby creating a lowered pressure in this vessel. Upon the release of the bulb 13, a quantity of liquid is forced from the container 6 through the tube 20 into the vessel 17, by virtue of the higher atmospheric pressure without upon the surface of liquid 21, this action serving to equalize both pressure within and without. The siphon, including both connecting tubes 15 and 19, as thus primed, will, upon the release of the clip 16, continue to flow until the surface of the liquid 21 in the container 6 has fallen to a point below the mouth or end of the short arm, or tube, 19 of the siphon proper, this continued action being due to the weight, or "pull" of the column of liquid in the vessel 7 and tube 15, constituting the longer arm of the siphon.

It is to be observed that, to insure perfect action, the air space in the chamber 17 above the nipple 18 must be of a volume equaling that of the compressible member 13 so that the amount of air remaining in this chamber, after exhaustion by compression of the member 13, may be sufficient to insure refilling of this member upon expansion to normal form, thus providing against possibility of the liquid entering therein. Should liquid enter the compressible member, it is obvious that it might cause deterioration of the compressible member.

Though, throughout, in the description, "flexible connections" have been referred to, it is not the intent to be so restricted, as it is apparent that these connections together with the chamber 17 may be of glass, or other suitable material, and made to constitute an integral unit, and, as well, that a valve might be substituted for the clip 16, though a valveless construction is primarily to be preferred.

Having thus described my invention, I claim, and desire to secure by Letters Patent:

In a siphoning device, a starter comprising a liquid containing vessel having a nipple at the top thereof, a second nipple at the side 15 of said vessel, said vessel terminating at the bottom in a third nipple, a fluid entrance pipe detachably connected to the second nipple, a fluid delivery pipe detachably connected to the third nipple, a valve in said fluid delivery 20 pipe, and a compressible bulb detachably secured to the first nipple, the cubic content of the vessel above the second nipple being substantially that of the compressible bulb.

In testimony whereof I hereby affix my 25 signature this 5th day of March, 1929.

PERCY VARNEY.
